UNITED STATES PATENT OFFICE

HARRY L. JOHNSON, OF WAUKEGAN, ILLINOIS, ASSIGNOR TO JOHNSON BROTHERS
ENGINEERING CORPORATION, OF WAUKEGAN, ILLINOIS

INTERNAL-COMBUSTION ENGINE

Application filed December 27, 1927. Serial No. 242,798.

The invention relates to internal combustion engines, particularly of the two-cycle type, and has for its object to provide a device of this character wherein the charge 5 is highly compressed in a restricted chamber in the under side of the piston upon the downward stroke thereof, and which charge at the end of the downward stroke is transferred through a by-pass port to the combustion chamber above the piston and fired, the exhaust taking place during the transfer operation.

A further object is to provide a closure between the cylinder and the crank case which 15 will restrict the compression chamber below the piston, thereby creating a greater suction in the carburetor and admitting more air, and providing a high compression of the gases before the transfer operation, and 20 which highly compressed gas is more speedily by-passed into the combustion chamber and facilitates a more rapid exhausting of the burnt gases, hence a higher operating speed of the engine is obtained.

25 A further object is to provide a closure cooperating with a cylinder and piston to produce a high compression chamber for the charge to be transferred, and means whereby the connecting rod may operate with a reciprocating and oscillating motion through the closure, and at the same time preventing material escape of gases during the compression thereof.

30 A further object is to provide the slideable plate with an annular flange bent to form an annular concave bearing for a ball through which the connecting rod is slidably mounted thereby reducing the parts to a minimum which is particularly desirable in a high 35 speed motor.

With the above and other objects in view the invention resides in the combination and arrangement of parts as hereinafter set forth, shown in the drawing, described and 45 claimed, it being understood that changes in the precise embodiment of the invention may be made within the scope of what is claimed without departing from the spirit of the invention.

50 In the drawing:

Figure 1 is a vertical longitudinal sectional view through the engine.

Figure 2 is a horizontal sectional view taken on line 2—2 of Figure 1.

Referring to the drawing, the numeral 1 designates the casing of the engine and 2 the cylinder, which cylinder and casing are provided with registering flanges 3, through which the bolts 4 extend for holding the same together. Disposed within the lower 55 end of the casing 2 and in spaced relation to the inner periphery thereof is an upwardly extending dome 5, the lower end of which is provided with a horizontally disposed flange 6, which extends between the flanges 3 and 60 is securely held by means of the bolts 4, therefore it will be seen that the dome 5 is rigidly supported in spaced relation to the inner periphery of the cylinder 2, and in a position where the skirt 7 of the piston 8 may pass 65 downwardly around the dome in spaced relation to the dome. The dome 5 forms means for extending upwardly into the compression chamber 9 of the piston for restricting the 70 content thereof, thereby allowing the gases taken in through the intake port 10 to be highly compressed before they pass through the piston skirt port 11, which registers with the lower end of the transfer port 12 when the piston 8 is at the lower end of its stroke. 75

When a charge is being compressed in the compression chamber 9, there is an exhaust operation from the combustion chamber 13 through the exhaust port 14, and during a portion of said exhaust operation the highly 80 compressed gas is bypassed through the by-pass port 12 into the combustion chamber 13, being deflected upwardly by the deflecting shoulder 15, thereby assisting in forcing the exhaust gases from the combustion chamber and directing the high compressed gases 85 away from the exhaust port.

The upper end of the dome 5 is provided with an elongated aperture 16 through which the connecting rod 17 extends, and which aperture is sufficiently elongated to allow freedom of oscillation of the connecting rod 90 during the rotation of the crank 18. Slidably mounted on the connecting rod 17 is a bearing ball 19, which bearing ball is rockably 95 100

mounted within the concave side of the annular flange 20, which flange is formed integral with a plate 21 slidably mounted in an elongated recess 22 in the upper end of the dome, therefore it will be seen that when the plate 21 is in position and is held slidably within the recess 22 by the removable plate 23, thereby allowing the connecting rod 17 to freely oscillate and at the same time forming a substantially gas tight connection. The engine is particularly adapted for high speed motor boats and the like, and where it is desired to obtain a very high compression and high speed irrespective of loss of fuel to a certain extent, for instance during the exhaust operation, or from any leakage around the connecting rod. Heretofore, in engines of this character, the crank case has been used as a compression chamber but the cubical content thereof is so large that a high compression can not be obtained, which objection is overcome by providing the dome and utilizing the chamber within the piston as a compression chamber, and by which structure it is obvious a relatively small compression chamber may be formed for high compression. While the above is a description of one form of the invention, it is obvious that other forms may be used to obtain the same result without departing from the spirit of the invention.

The invention having been set forth, what is claimed as new and useful is:—

1. The combination with an internal combustion engine having a cylinder, a piston, and a connecting rod carried by said piston and adapted to have a reciprocating and an oscillating movement, of a closure extending within and cooperating with said cylinder to form a compression chamber, said connecting rod operating through said closure, and means shiftable along a substantially straight path, associated with said closure and connecting rod to maintain said closure intact in the movements of the connecting rod.

2. The combination with an internal combustion engine having a cylinder, and a piston slidable in said cylinder, a connecting rod carried by said piston, of a closure extending into the piston and cooperating with the cylinder to form a compression chamber, said connecting rod operating through a member carried by said closure and oscillatable along a substantially straight path.

3. The combination with an internal combustion engine having a cylinder, a piston, and a connecting rod carried by said piston, of a closure extending into the piston and cooperating with said cylinder to form a compression chamber, said closure carrying a movable closure means through which said connecting rod operates and is controlled by the movement of the connecting rod, said closure means having a substantially straight line movement.

4. The combination with a chambered piston mounted in a cylinder, of a dome having a substantially flat upper portion extending into said chamber in the movement of the piston and cooperating with the piston to form a compression chamber.

5. The combination with a chambered piston slidably mounted in a cylinder, a connecting rod, of a dome having a substantially flat upper portion extending into the chamber of the piston in the movement of the piston, said connecting rod operating through said dome.

6. The combination with a chambered piston slidably mounted in a cylinder, and a connecting rod carried by the piston, of a dome having a substantially flat upper portion adapted to extend into said chamber during the movement of the piston, said connecting rod extending through the dome and having an oscillating and reciprocating relation thereto.

7. The combination with a two-cycle internal combustion engine of the transfer type, of a dome having a substantially flat upper portion extending upwardly into a compression chamber of a piston, a connecting rod carried by said piston, said connecting rod having an oscillating and reciprocating connection with the dome.

8. The combination with a piston slidably mounted in a cylinder and having a chamber in the under side thereof and transfer means to the upper side of the piston, of a dome telescoped by the piston having a substantially flat upper portion, said connecting rod operating through said dome.

9. The combination with an internal combustion engine having a cylinder, a piston slidable in said cylinder, a connecting rod carried by said piston, of a dome mounted in said engine and adapted to be telescoped by said piston, said dome carrying a slidable member through which the connecting rod operates, said member being slidable along a substantially straight path.

10. The combination with an internal combustion engine having a cylinder, a piston, and a connecting rod carried by said piston, of a dome adapted to be telescoped by said piston, said dome carrying a movable closure means through which said connecting rod operates, said closure means being movable along a substantially straight path.

11. The combination with an internal combustion engine having a cylinder, a piston, and a connecting rod carried by said piston, of a dome adapted to be telescoped by said piston, said dome carrying a movable closure means through which said connecting rod operates and is controlled by the movement of the connecting rod, said closure means being movable along a substantially straight path.

12. The combination with a piston slid-

ably mounted in a cylinder and having a chamber in the under side thereof and transfer means to the upper side of the piston, a connecting rod carried by the piston, of a dome extending upwardly into the chamber of the piston and forming the bottom of a combustion chamber, a slideable bearing carried by said dome, said connecting rod being slidably mounted in said slideable bearing, said bearing being slideable along a substantially straight path.

13. The combination with an internal combustion engine having a piston into which a dome extends, which dome forms the bottom of a compression chamber, a connecting rod carried by said piston, of a member slidably mounted in the dome and forming a closure for an opening through which the connecting rod extends, a ball slidably mounted on the connecting rod, and an annular, upwardly extending, concave flange carried by the slideable member and in which the ball is rockably mounted.

14. The combination with an internal combustion engine piston having an oscillating connecting rod, a dome forming a wall of a compression chamber, of a connection between said connecting rod and dome, said connection comprising a plate slidably mounted in a recess of the dome, a retaining plate for said last named plate, said first named plate having an annular, upwardly extending, flange, a ball rockably mounted in said flange, said connecting rod being slidably mounted in said ball.

15. An internal combustion engine comprising a cylinder having an exhaust port and an intake port, a by-pass port, a chambered piston slidably mounted in said cylinder, a dome carried by said cylinder and having a flat top adapted to extend into the chamber of the piston close to the under side of the piston in its outermost position and restrict the cubical content thereof on compression strokes, a connecting rod carried by said piston, said connecting rod having a substantially gas tight rockable and transversely slideable bearing connection with the flat top of the dome.

16. An engine comprising a flanged cylinder, a piston, an outwardly flanged crank case, a crank shaft, of a partition secured between the flanged ends of the cylinder and crank case having a flat-topped dome extending upwardly into the cylinder closely adjacent the piston pin connection, and a connecting rod connecting the piston and crank shaft having means providing a substantially gas tight transversely slideable movement through the dome of said partition.

17. The combination with a piston slidably mounted in a cylinder, a crankshaft, a connecting rod attached to said piston and shaft, and said rod reciprocating and oscillating through an opening in a horizontally

reciprocable plate, of dome shaped means whereby the opening in the plate is maintained substantially closed.

18. In combination with a cylinder and a crank case of an internal combustion engine and a piston slideable within said cylinder, of a closure means co-operating with said cylinder to form a restricted compression chamber, a connecting rod carried by said piston and extending through said closure, slideable means carried by the closure and actuated by the connecting rod to maintain a seal between the closure and the connecting rod during the reciprocating and oscillating movement of the latter, and a removable cover member to permit the removal of the slideable means carried by said closure.

19. The combination of an internal combustion engine having a cylinder, a piston and a connecting rod reciprocable therein, of a closure co-operating with said cylinder to form a compression chamber, said closure co-operating with and extending upwardly within said cylinder to provide a restricted compression chamber, and means horizontally slideable within said closure for receiving said connecting rod so as to maintain a seal between said closure and said connecting rod during the reciprocation and oscillation of the latter.

In testimony whereof I affix my signature.
HARRY L. JOHNSON.
